UNITED STATES PATENT OFFICE.

ADAM M. GOODWIN AND JESSE N. WEAVER, OF PITTSBURGH, PENNSYLVANIA.

MECHANICAL DIGGER.

1,238,509.

Specification of Letters Patent. Patented Aug. 28, 1917.

Application filed January 25, 1917. Serial No. 144,325.

To all whom it may concern:

Be it known that we, ADAM M. GOODWIN and JESSE N. WEAVER, of the city of Pittsburgh, in the county of Allegheny and State 5 of Pennsylvania, have invented a certain new and useful Improvement in Mechanical Diggers, of which the following is a full, clear, and exact description, reference being had to the accompanying drawings, forming 10 part of this specification, in which—

Figure 1 is a plan view illustrating our invention; Fig. 2 is a side elevation of the same; Fig. 3 is a vertical cross section on the lines $c-c$, $c-c$ of Fig. 1; Fig. 4 is an enlarged elevation of a portion of the apparatus, illustrating the excavator; Fig. 5 is a vertical cross section on the line $y-y$ of Fig. 2; Fig. 6 is an elevation illustrating the rear elevator; and Fig. 7 is a detached view 20 of the elevator leading from the excavator and of the central conveyer.

Our invention relates to apparatus for excavating material at the sides of railway tracks, for screening the material excavated, 25 and for depositing or disposing of the same. It is specially adapted to the cleaning and relaying of ballast at the sides of the track, which, from time to time, must be done in order to remove accumulations 30 of dust and cinder, and also to correct irregularities due to displacement; and, although we do not desire to limit our invention to this use, we have shown in the drawings a form of apparatus designed for this purpose.

35 In the drawings we have shown an apparatus consisting substantially of a car A having trucks B adapted to travel on the rails of a track, on which car is mounted one or more excavators, preferably one at each 40 side of the car, which excavators are adapted to be raised and lowered vertically to regulate the depth of the excavation, and also to be swung to a position over the car, moving on the arc of a circle, to prevent interference of the excavator with trains on the 45 adjoining track or with other obstacles. It also consists in a screen, a series of conveyers and elevators, and operating mechanism and motors, all of which are mounted on the 50 car and arranged to be operated by a minimum number of workmen.

We will now describe our invention so that others skilled in the art may manufacture and use the same.

55 In the drawings we have shown a flat-car A, the trucks of which may be driven by an

electric motor connected with the axle of the truck by suitable gears, power being transmitted to the motor from the dynamo 62 through the controller 63', the dynamo 60 being driven by the steam engine 61 which is connected with the steam dome of a locomotive by a flexible hose 63, the locomotive being coupled to the car A to serve merely 65 as a steam generator.

At each side of the car is an excavator 2 which consists of a rotary drum having serrated blades and pockets adapted to cut into and lift the ballast, the drum being fixed to a shaft 5 which is journaled in a saddle 60', 70 which is suspended from the swinging frame 23. Keyed to the shaft 5 is a sprocket wheel 3 which is connected with the sprocket wheel 4 by a chain 6, the wheel 4 being keyed to a shaft 7 which is mounted in the housing 75 7' fixed to the frame 23, the shafts 5 and 7 being journaled in bars 2', which act as bearings for the shafts. The frame 23 is fixed to the hollow shaft 21, which shaft is journaled in housings 22 secured to the car 80 A, thus forming a pivotal connection between the car and the frame. Keyed to the inner end of the shaft 7 is a miter wheel 8 which meshes with a miter wheel 8a which is keyed to the inclosed shaft 9. This shaft 85 9 is driven by the spiral gear 10 and the spiral 11, which spiral is fixed on the shaft 12, which is driven by the gear 13, which meshes with the connecting gear 14 driven by the motor pinion 15, which pinion is 90 fixed on the motor shaft 16 driven by the electric motor 17, which is connected with the controller d. The spiral gear 10, which is mounted loosely on the shaft 9, may be fixed thereto by means of the sliding clutch 95 18 which is operated by the piston of the pneumatic cylinder 19, which is controlled by the air valve 20, thus permitting the shaft 9 and the excavator 2 to be thrown out of 100 operation without stopping the motor.

Encircling the shaft 9 is the hollow shaft 21 which is journaled in the housings 22 which are fixed to the car, and fixed to the shaft 21 is the frame 23 which supports the excavator 2. Keyed to the shaft 21 is 105 a spiral gear 24, which meshes with the spiral 25 on the shaft of which is loosely mounted a spiral gear 26, which meshes with a spiral 27, which is keyed to one end of a shaft 28, at the other end of which 110 shaft is a spiral gear 29, which meshes with a spiral gear 30, which is keyed to the shaft

12, which, as has been stated, is driven by the gears 13, 14 and 15 by the motor 17. The purpose of this is to enable the excavator to be swung upwardly over the car, 5 moving on the arc of a circle, by the partial rotation of the shaft 21, the parts being thrown into operation by the clutch 64, which is brought into engagement with the gear 26 by the piston of the air cylinder 65, 10 which is operated by the valve handle 66.

To enable the excavator 2 to be raised and lowered vertically to regulate the depth of the excavation, a screw 60 extends upwardly from the top of the saddle 60' through 15 cavities in the upper and lower lips formed at the end of the arm 23^a of the frame 23, and through a threaded nut 59 located between the two lips. The outer face of the nut 59 is provided with a spiral gear which 20 meshes with a spiral 58 which is keyed to the shaft of the small motor 57. To permit of this vertical movement the journal boxes of the shaft 5 in the bars 2' should be loosely fitted in the bars.

25 As the ballast, or other material, is excavated it is carried away by a series of conveyers and elevators. Back of the excavator 2 is a conveyer 31 one end of which is supported by the straps 31' connected 30 with the bar 2' and the other end is supported by the driven shaft 8'', thus allowing the conveyer to swing with the frame 23. In the rear of the discharge end of the conveyer 31 is a short elevator or conveyer 32 which is mounted on the idler shaft 32' at one end, and on the driven shaft 32'' at the other end, both of which shafts are journaled in bearings fixed to the frame of the car. The shafts 32', 32''

40 are driven from the shafts 33^a and 70 of the central conveyer 33 through the miter wheels 33^b and 33'', the shaft 33^c, and the miter wheels 33^d and 33'. Midway between the two excavators is the central conveyer 45 33 into which the conveyers 32 discharge. This conveyer 33 is mounted at one end on the shaft 33^a and at the other end on the shaft 70, the shaft 33^a being driven by the conveyer, and the shaft 70 by the shaft 67 of 50 the elevator 34 through the gear wheels 68, 69 and 69'. At the end of the conveyer 33 is an elevator 34 which is mounted on the shafts 67 and 48', the upper shaft 48' being driven by the sprocket 53' which is driven 55 by the motor 41 through the gears 42, 43, shaft 44 and spiral gears 50, 52 and the sprocket 53; the gear 52 meshing with a spiral 50 on the shaft 51 which carries the sprocket 53 which is connected by a chain 60 with the sprocket 53' on the shaft 48'. Below the upper end of the elevator 34 is the chute 35 at the bottom of which is a conveyer 46 which is driven by the shaft 47 which is provided with a sprocket and a

65 chain leading to the sprocket 48 on the shaft 48'. This chute 35 leads to the hopper 36 which discharges into the inclined drum-screen 37 which is supported by rollers journaled in the standards 37', the screen being caused to revolve by the gear wheel 45'' which meshes with the gear 45' which is driven by the gear 45 fixed to the shaft 44' which is driven from the motor 41 through the gears 43 and 42. The lower end of the drum 37 is open and arranged to 70 deposit the ballast free from dust and cinder into the hopper 38 and chute 39 and thence on or at the sides of the track. Below the screen 37 is an inclined boot 39' which is adapted to receive the fine material, cinder 75 and dust that passes through the mesh of the screen, and at the lower portion of this boot is an elevator 40 which is mounted on an upper and a lower shaft, the upper shaft having a sprocket 56 which is driven by a 80 chain extending to the sprocket 54' on the shaft 55, which shaft is driven by a sprocket 54 which is connected by a chain with the sprocket 53'' on the shaft 51. Below the 85 upper end of the elevator 40 is a swiveled 90 hopper and chute 40' arranged to deposit the fine material either away from the track or on a car coupled to the car A.

The operation is as follows:—During the 95 passage of the car A on the track of the railway, the excavators are in their raised position over the car, as is indicated in Fig. 3 by the dotted lines, thus keeping them out of the way of obstacles at the side of the track. When, however, the car reaches its destination, the place where the excavating is to begin, the car A and the locomotive which has been pulling the car are brought to a stand, the operator moves the controller handle *d* which starts the motors 17, which puts 100 the shafts 12 and 28 in motion, and also the worms 11 and 27, which drives the worm wheels 10 and 26. The air valve 66 is then moved to admit air into the cylinder 65, which moves the clutch 64 into the worm 105 gear 26 and starts the shaft 25' on which is fixed the worm 25 which drives the worm wheel 24 fixed to the hollow shaft 21, which carries the frame of the excavator 2, and as the shaft revolves, the excavator 2 is 110 swung to the side of the car, whereupon the clutch is thrown out by reversing the air valve 66. The excavator is then lowered to the depth of the excavation desired by throwing the switch to start the motor 57 115 connected with the screw 60. To start the rotation of the excavator, the operator then moves the air valve 20 to admit air into the cylinder 19 and throw the clutch 18 thus starting the shaft 9, gears 8 and 8^a, and the shaft 7 which drives the gear 4, which is connected by the chain 6 to the gear 3 by which the excavator is driven. By means of the controller 63' the motor which drives 120 the car is then started which drives the car 125 130

forward causing the teeth of the excavator to bite into the ballast, at the same time the operator at the rear of the car starts the motor 41 which drives the elevators 34 and 40, 5 the revolving screen 37 and the conveyer 33. In passing curves in the track it becomes necessary to move one of the excavators outwardly in order to clear the ties, and this is done by swinging the frame 23 partially up- 10 ward by throwing the clutch 64, as is shown in Fig. 3.

By the use of our invention ditches may be excavated rapidly and efficiently, and the ballast at the sides of railways may be 15 cleaned and relaid economically, three workmen being sufficient to operate the apparatus. From the foregoing description these and the other advantages of our invention may be appreciated by those skilled in the art.

20 What we claim is:

1. In a mechanical digger, the combination of a railway car, a rotatory excavator journaled in a saddle suspended from a swinging frame, a hollow shaft to which the 25 swinging frame is fixed, a power shaft within the hollow shaft, devices connecting the power shaft with the driving mechanism of the excavator, devices for driving the hollow shaft, and devices for raising and lowering 30 the excavator to regulate the depth of the excavation.

2. In a mechanical digger, the combination of a railway car, a rotatory excavator journaled in a saddle suspended from a 35 swinging frame, a power shaft journaled in bearings fixed to the car, an intermediate shaft journaled in bearings connected with

the swinging frame, miter wheels connecting the intermediate shaft with the power shaft, and a chain and sprockets for imparting 40 power from the intermediate shaft to the excavator.

3. In a mechanical digger, the combination of a railway car, a rotatory excavator journaled in a saddle suspended from a 45 swinging frame, a motor and connecting mechanism for imparting a rotatory movement to the excavator, connecting mechanism for swinging the frame on the arc of a circle, and a motor and mechanism for 50 raising and lowering the excavator vertically to regulate the depth of the excavation.

4. In a mechanical digger, the combination of a railway car, a rotatory excavator 55 journaled in a saddle suspended from a swinging frame, devices for raising and lowering the excavator vertically, a conveyer mounted at one end on the swinging frame and at the other to a driven shaft on the 60 car, a power shaft, devices for connecting the power shaft with the excavator, devices for connecting the power shaft with the conveyer, devices for swinging the frame on the arc of a circle, a motor, and a clutch for 65 throwing the power shaft in and out of connection with the motor.

In testimony whereof, we have hereunto set our hands.

ADAM M. GOODWIN.
JESSE N. WEAVER.
